RACK FOR FLOOR COVERINGS AND
THE LIKE

John H. Miller, Chicago, Ill.

Application August 28, 1935, Serial No. 38,159

1 Claim. (Cl. 242—55.3)

This invention is concerned with a rack mounting one or more spindles on each of which may be wound a floor covering such as linoleum. It is an object of my invention to devise for this purpose a rack which is simple and inexpensive in construction, which will occupy a minimum of space, which will accessibly support a number of rolls of linoleum or other products, which may be operated with little or no effort to unwind and remove a desired quantity of linoleum or other products, and which will permit of new rolls being placed in or out of use with a minimum of time and effort.

A suggestive exemplification of my invention is illustrated in the accompanying drawing wherein—

Figure 1 is a front elevation of the rack; Fig. 2 is an enlarged vertical section there-

20 through on line 2—2 of Fig. 1; Fig. 3 is a view in plan of one of the turn-

tables, taken as suggested by line 3 in Fig. 1; and Fig. 4 is a perspective view of the lower portion of one of the spindles.

The present rack comprises an elongated base 25 B in the form of a plank or rail above which is a head H also in the form of a plank or rail. The base may be positioned upon a floor F ad- jacent a wall W and the head may conveniently be carried on the wall at an elevated point, all 30 as clearly shown in Fig. 2.

The base is provided at spaced intervals with openings in each of which is fitted a bushing 5 forming a bearing for a trunnion 6 which de- 35 pends from a turntable 7 having an axial non-round socket 8. The underside of each turn- table is rested upon a group of rollers 9 each having a rotatable mounting in a frame 10 that is affixed to the upper surface of the base. It is apparent that with the parts so formed and ar- 40 ranged each turntable is free to revolve about a fixed vertical axis.

For each turntable I may provide a spindle S having at its lower end a cap 15 with a depend- 45 ing boss 16. This boss is of a cross sectional form to be received non-rotatably within the socket 8 of the turntable. As shown, the lower end of the spindle over which the cap is fitted is adapted to rest upon a shoulder 17 formed in the turntable.

50 The upper end of each spindle is adapted for journaling within a bearing 20 that is afforded by a block 21 having a hinged mounting at 22 with the head H. Each block, as shown, has capacity for down-swinging from an upper vertical position to a horizontal position where it is sustained by engagement with the head. In this position the block serves to provide a bearing for the upper end of the spindle which is free to rotate therewithin.

As shown clearly in Fig. 1, a number of turn- 5 tables may be positioned upon the base with their axes in substantial alignment. Likewise a corresponding number of bearing blocks may be carried by the head, one in opposition to each 10 turntable. A spindle may thereupon be positioned upon each turntable with its upper end journaled within the opposed bearing, and when so secured in place will be free to rotate together with its supporting turntable. Each spindle is 15 adapted to serve as a core for a roll R of lino- leum or other material which is wound there- upon, the lower edges of the convolutions of the roll being rested upon the associated turntable. In use the exposed vertical edge of the linoleum 20 may be pulled out to unwind and remove a quantity of the material, and in this operation the turntable revolves freely.

It will be noted that each spindle will serve as 25 a core for the windings of the linoleum, and that the entire roll, with the spindle inside, may be fitted in place upon the turntable. This re- 30 quires merely that the roll with spindle there- within be lifted to a position which will allow the spindle to drop into the turntable socket, the roll then resting upon the turntable. As part of this operation the upper end of the spindle may be fitted in the bearing block, or the bearing block may subsequently be swung down into 35 engaging position with the upper end of the spindle to complete the rotatable mounting therefor.

I claim:

A rack for rolls of linoleum and like floor 35 coverings, comprising an elongated rectangular base member having a plurality of longitudinally spaced sockets formed therein, a circular series 40 of roller carrying frames mounted rigidly upon the base around each of said sockets with the axes of the rollers of each series fixedly disposed radially of the respective socket axis, a freely 45 removable turntable provided with a depending trunnion journaled in each of said sockets, the under side of each turntable adjacent the periphery thereof providing a runway for said rollers and the sole support for the turntable, a 50 socket having a non-round lower portion formed in the upper face of each of said turntables, a roll centering spindle for each turntable having its lower end shaped to fit snugly within the 55 socket thereof and non-rotatably engage the non-round lower portion of the socket, and a block mounted to swing into a horizontal position over a roll supported upon a turntable and having a bearing therein adapted to receive and 55 rotatably support the upper end of the spindle.

JOHN H. MILLER.
